Brett P. Belden; Foley & Lardner LLP

(57) **CLAIM**

We claim the ornamental design for an ultrasound cart, as shown and described.

DESCRIPTION

FIG. 1 is a top, front, left perspective view of the claimed design;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof;

FIG. 7 is a bottom plan view thereof;

FIG. 8 is a top, front, left perspective view of another embodiment of the claimed design;

FIG. 9 is a front elevation view thereof;

FIG. 10 is a rear elevation view thereof;

FIG. 11 is a left elevation view thereof;

FIG. 12 is a right elevation view thereof;

FIG. 13 is a top plan view thereof; and,

FIG. 14 is a bottom plan view thereof.

The broken lines illustrate portions of the ultrasound cart that form no part of the claimed design.

1 Claim, 14 Drawing Sheets
